Perkins Davis Marvin & Edwards

UNITED STATES PATENT OFFICE.

GEOERGE H. ZOUCK, OF ORANGE, NEW JERSEY, ASSIGNOR TO AIR REDUCTION COMPANY, INC., A CORPORATION OF NEW YORK.

BLOWPIPE.

1,310,104.

Specification of Letters Patent. Patented July 15, 1919.

Application filed December 4, 1918. Serial No. 285,195.

To all whom it may concern:

Be it known that I, GEORGE H. ZOUCK, a citizen of the United States, residing at Orange, in the county of Essex, State of New Jersey, have invented certain new and useful Improvements in Blowpipes; and I do hereby declare the following to be a full, clear, and exact description of the invention, such as will enable others skilled in the art to which it appertains to make and use the same.

This invention relates to blow-pipes or torches, and has for its primary object, the provision of an inexpensive simple and efficient blow-pipe or torch structure, in which the gas inlet passages are securely sealed to prevent leakage or premature mixing of the gases, including replaceable tips capable of producing flames of varying dimensions and constructed to insure a proper relation by volume of combustible and oxidizing gases delivered to the discharge passage of the tip.

Further objects and advantages of the invention will be apparent as it is better understood by reference to the following specification when read in connection with the accompanying drawing illustrating the preferred embodiment thereof, in which—

Figure 1 is a longitudinal section through the head and tip of a blow-pipe or torch;

Fig. 2 is a transverse section through the head, on the line 2—2 of Fig. 1;

Fig. 3 is an end elevation of the tip.

Blowpipes as heretofore constructed are all more or less complicated in structure and require intricate operations in their manufacture. Leakage, improper and premature mixing of the gases, liability to backfiring and expensiveness of construction are but a few of the common faults of such blowpipes. The blowpipe forming the subject matter of the present application overcomes these defects and provides a structure which combines with the utmost simplicity, all of the desirable characteristics of an efficient blowpipe, particularly the proportioning of the mixture by the tip so that a proper mixture for tips delivering flames of varying sizes is assured without manipulation by the operator, other than the substitution of a tip of the required size.

Referring to the drawing, 5 indicates a head to which two pipes 6 and 7 are secured, whereby a supply of oxygen and of com-

bustible gas are separately delivered to the head. Within the head two passages 8 and 9 are provided, the former communicating with the oxygen pipe 6 and the latter communicating with the pipe 7 carrying com- 60 bustible gas.

The head 5 is provided with a projecting conical seat 10, at the apex of which the passage 8 terminates. The passage 9 terminates in an annular channel 11 in the seat 10 and a similar and concentric channel 12 is formed in the seat substantially midway between the channel 11 and the passage 8. One or more ducts 13 connect the channel 12 to the passage 8. 70

The tip 14 is secured to the head 5 by a coupling 15 and is provided at its inner end with a conical recess conforming to and forming with the conical surfaces on either side of the channels 11 and 12, gas tight seals which prevent leakage of the gases, or mixing other than in the manner and proportions determined by the structure, as herein-after described. 75

The inner end of the tip 14 has one or more grooves or depressions 15 on its conical surface, which may be formed by milling, pressing or otherwise, the groove or grooves being radially directed and of a length sufficient only to provide communication between the channels 11 and 12 when the tip is assembled with the head. The groove or grooves 15 are accurately proportioned to the size of the delivery passage 16 extending longitudinally of the tip in alignment with the passage 8 in the head. 80 85 90

As will be readily understood, oxygen in the passage 8 is met by a quantity of combustible gas, accurately proportioned by 95 passage through a groove or grooves 15 and issuing through the ducts 13. The oxygen and combustible gas are mixed in the passage 8 and pass into the discharge passage 16 of the tip and at its outlet are ignited 100 and burned.

Tips having discharge passages of different sizes are interchangeable with a single head and the groove or grooves 15 are accurately formed to permit the proportion of 105 combustible gas, adapted to produce the best results with the particular size of discharge passage, to enter and mix with the stream of oxygen.

As will be immediately apparent, the 110

structure is exceedingly simple both in form and in the operations required in its manufacture. No part of the blowpipe is liable to wear in service, which will materially affect its operation and none of its parts are liable to injury even by careless use.

Various changes may be made in the form, arrangement and proportioning of the parts without departing from the spirit or scope 10 of the invention or sacrificing any of its material advantages, the form hereinbefore described being merely the preferred embodiment thereof.

I claim:

15 1. A blowpipe comprising a head and a separable tip, said head and tip having coöperating surfaces forming a gas tight joint, passages in said head for oxidizing and combustible gases, a discharge passage in said tip communicating with the oxidizing gas passage in said head and means for delivering combustible gas from the passage therefor in said head to said oxidizing gas passage whereby the gases are mixed with 25 in said head, including means in the tip and removable therewith to regulate the proportion of combustible gas delivered to said oxidizing gas passage.

2. A blowpipe comprising a head and a separable tip, said head and tip having coöperating surfaces forming a gas tight joint, passages in said head for oxidizing and combustible gases, a discharge passage in said tip communicating with the oxidizing gas 30 passage in said head, a channel in one of said surfaces communicating with the combustible gas passage, a concentric channel in one of said surfaces communicating with the oxidizing gas passage and a groove in 35 the surface of said tip connecting said channels to regulate the proportion of combustible gas supplied to said oxidizing gas passage.

3. A blowpipe comprising a head and a separable tip having coöperating surfaces forming a gas tight joint, passages in said head for oxidizing and combustible gases, a discharge passage in said tip communicating with the oxidizing gas passage in said 45 head, a duct in said head communicating with said oxidizing gas passage, and a groove in the surface of said tip connecting the combustible gas passage to said duct when the head and tip are in assembled relation.

4. A blowpipe comprising a head and a separable tip having coöperating conical

surfaces forming a gas tight joint, passages in said head for oxidizing and combustible gases terminating in the conical surface of 60 said head, a groove in the conical surface of said tip communicating with the combustible gas passage when the head and tip are in assembled relation, a duct in said head whereby combustible gas passing through 65 said groove is delivered to the oxidizing gas passage and a discharge passage in said tip communicating with said oxidizing gas passage.

5. A blowpipe comprising a head and a separable tip, said head having a projecting conical seat and said tip having a conical recess at its end conforming to said seat and forming therewith a gas tight joint, oxidizing and combustible gas passages in said 75 head, a duct extending through said conical seat to the oxidizing gas passage, a groove in the surface of said conical recess whereby the combustible gas passage is connected to said oxidizing gas passage when the head 80 and tip are in assembled relation and a discharge passage in said tip communicating with said oxidizing gas passage.

6. A blowpipe comprising a head and a separable tip, said head having a projecting 85 conical seat and said tip having a conical recess at its end conforming to said seat and forming therewith a gas tight joint, oxidizing and combustible gas passages in said head, concentric channels in said conical 90 seat communicating respectively with the oxidizing and combustible gas passages, a groove in surface of said conical recess connecting said channels when said head and tip are in assembled relation and a discharge 95 passage in said tip communicating with said oxidizing gas passage.

7. A blowpipe comprising a head and a separable tip, said head having a projecting seat and said tip having a recess conforming to said seat and forming therewith a gas tight joint, oxidizing and combustible gas passages in said head, concentric channels in said seat, the combustible gas passage terminating in one of said channels, a duct 105 connecting the other of said channels to the oxidizing gas passage, a groove in the surface of said recess connecting said channels when the head and tip are in assembled relation and a discharge passage in said tip 110 communicating with said oxidizing gas passage.

In testimony whereof I affix my signature.
GEORGE H. ZOUCK.
